A. WATSON.
TERMINAL FOR PNEUMATIC DESPATCH TUBE SYSTEMS.
APPLICATION FILED NOV. 7, 1919.

Patented July 20, 1920.

UNITED STATES PATENT OFFICE.

ALEXANDER WATSON, OF ATLANTIC, MASSACHUSETTS, ASSIGNOR OF ONE-HALF TO
WILLIAM G. MITCHELL, OF MALDEN, MASSACHUSETTS.

TERMINAL FOR PNEUMATIC-DESPATCH-TUBE SYSTEMS.

1,347,136.

Specification of Letters Patent.

Patented July 20, 1920.

Application filed November 7, 1919. Serial No. 336,255.

To all whom it may concern:

Be it known that I, ALEXANDER WATSON, citizen of the United States of America, and resident of Atlantic, in the county of Norfolk and State of Massachusetts, have invented new and useful Improvements in Terminals for Pneumatic-Despatch-Tube Systems, of which the following is a specification.

10 This invention relates to pneumatic despatch tube systems of the type having a despatch tube normally at atmospheric pressure only, and in which the transmission of the carrier is effected by pressure behind the carrier.

As shown, described and claimed in my Letters Patent of the United States No. 1,159,627, dated November 9, 1915, I have heretofore provided means for the introduction of a charge of compressed air at the rear end of a despatch tube behind a carrier inserted therein, including a valve or cover for closing the despatching entrance to the tube, and an air introduction valve 20 opened by the motions of the mounting for the despatch tube closing valve or cover. This prior system provides an air admission valve of the balanced type in which the pressure tending to hold the valve upon its seat is released upon the final part of the motion of the mounting for the despatch tube cover, and also provides for the closure of the air admission valve upon the resumption of balanced pressures after this event, and independently for opening the closure or cover for the despatch tube automatically upon cessation of carrier despatching pressure at a point near the despatching terminal.

40 In the practical operation of devices according to said patent some situations are encountered in which the automatic closure of the admission valve and opening of the despatch terminal is delayed too long by reason of pressure or air-currents continuing in the despatch tube near the despatch end. This is particularly the case when the system includes transmission lines of greatly different lengths or when it is 45 desired to operate it under very high initial pressures. In some cases the pressures at the despatch terminal are such as not only to delay the closure of the admission valve and opening of the despatch terminal closure but entirely to prevent closure of the air

admission valve, or to delay opening of the terminal closure unduly, or both, and in either case uselessly to cause a flow of air.

The present invention has for its principal objects to prevent the waste of energy 60 in such systems, and to improve the device of said Letters Patent by causing automatic cessation of air flow in an improved manner promptly upon delivery of the carrier at a distant station, no matter what 65 may be the length or condition of the despatch tube to which it may be applied; to insure the automatic opening of the despatch terminal closure in response to the delivery of the carrier at the far end of the 70 system whether or not the air-admission valve has meanwhile closed; and thus to insure the prompt automatic closure of the air admission valve as a consequence of the opening of the terminal cover or valve. 75

Further objects are to improve the mechanical constructions of the patented device to secure increased durability, rigidity, strength and simplicity, and to render the devices employed less wasteful in the hands 80 of ignorant users; to avoid wasteful flow of air when no carrier is to be despatched, and to provide convenient adjustments by which the automatic admission of air for operating a particular despatch tube line may be 85 certainly secured and delicately regulated.

I shall describe the invention, which is independent of any particular mechanism, in connection with a specific preferred instance of a construction selected to illustrate the genus. In the accompanying drawings,—

Figure 1 is a vertical sectional view partly in elevation of an air admission valve and terminal closure corresponding to the 95 present invention;

Fig. 2 is a section on line 2—2 of Fig. 1; and

Fig. 3 is a detail section on line 3—3 of Fig. 1. 100

Referring now to Fig. 1 the terminal comprises as a whole a hollow, preferably cast-metal, casing A including a portion 1 fitting over the end of the despatch tube 2, and including the cylindrical casing A' of 105 my said prior Letters Patent No. 1,159,627, having therein a cylindrical valve chamber A² formed in a partition A⁴ separating the pressure compartment Y from the pressure delivery compartment Y', and having there- 110

in a seat A^5 for a valve C controlling communication between a port a leading from the compartment Y , and a port a' leading into the compartment Y' and to the despatch tube 2.

As explained in said patent the valve C is held upon its seat by an attached piston C^2 of greater area than the valve and having a suitable packing, working in the cylindrical chamber A^3 , and subject to the pressure in the part of the chamber A^3 above the piston C^2 . Normally pressure in the chambers Y , A^3 is the same as pressure in the air-supply pipe B with which the chamber Y communicates. Pressure in the upper part of the chamber A^3 above the piston C^2 is slowly equalized with the pressure beneath the piston C^2 through a port C' adjusted by plate C^3 , as explained in said patent. Pressure above the piston C^2 is released to operate the valve C by motion of a hollow rod E carrying a valve E' controlling the central opening in the rod leading into a bore in valve C in which rod E slides. By this arrangement pressure downward upon the head G of rod E against a spring F releases the pressure in the upper part of the chamber A^3 and permits valve C to be opened by the unbalanced pressure from chamber Y on the lower side of the piston C^2 , which is larger in area than the valve C . When pressure on the rod E and head G is released, pressures on the upper and lower sides of the piston C^2 become balanced after a time determined by the working pressure and the width of the port C' , and at some time prior to balance of these forces, the valve C seats on the seat A^5 by reason of lesser pressure in the chamber Y' , than in the chamber Y . Of course this does not occur until the valve E' is closed or partially closed, nor until the pressure in the chamber Y' and tube 2 supplied by the air admission valve C has dropped below the pressure in the supply pipe B to a marked extent.

As also explained in said patent, effective opening of the air admission valve C is arranged not to occur until after the manual closing of a cover or despatch tube closure valve O arranged to seat on a boss a^5 of the part of the casing in which the despatch tube 2 terminates. The valve O comprises a suitable metal casing having a locking lug O^2 , and an elastic and compressible packing O^3 for the seating disk O^4 , and having a central stem P surrounded by a spring s .

The casing O is integral with and attached to arms O' pivoted concentrically with a shaft N extending between integral brackets M projecting from the casing A . Instead of mounting the valve O as shown in said patent, I prefer to provide the arms O' with comparatively large bearing rings O^5 free to turn upon a tubular shaft 10

having a bearing at one end on the shaft N and at the other end on the plug 11 seated in one of the brackets M and preferably held in predetermined rotary adjustment by a set screw 12. The plug 11 is bored to receive one end of the shaft N which extends through a bore in the other bracket M and is held against endwise movement by a screw plug 11^a. Within the tubular shaft 10 a strong spring 13 for opening cover O reacts between a bore 14 in the end of the tubular shaft 10 and a bore 11^b in the plug 11, and said spring may be adjusted by rotating plug 11 and setting the adjustment by set screw 12.

Tubular shaft 10 is attached to or integral with an operating handle 15 provided with a central recess 16 to take over the spring S and further provided with internally hollow lateral bosses 17 into which pins 18 on the arms O' take for a slight freedom of independent movement between the arms O' and the operating handle 15, as will be permitted when the disk O^4 seats on the seat a^5 and the spring S is further compressed by further motion of the handle 15.

This further motion of the handle 15 is relied upon to fully depress the operating stem E of the compressed air admission valve C . A bell crank lever 20 is pivoted on a transverse pin 21 between lugs 19 on the casing in such a position that its arm 22 is struck by a lug 23 on the handle 15 after the disk O^4 is seated at a^5 and as a consequence of a further movement of the handle 15.

The normal open position of the handle 15 under impulsion of the spring 13 is limited by a lug 25 taking against one of the lugs 19.

In my said patent provision was made to latch the cover or valve O in place until release of the pressure in the entrance end of the despatch tube was effected.

On a very long transmission line or with a sticking carrier it sometimes happened that pressure continued to be maintained in the entrance end, and the valve O remained locked; and in an aggravated case this back pressure in the despatch tube 2 was sufficient to prevent seating of the air admission valve C . In order to operate the latch to release the valve O of said patent, a spring pressed plunger was arranged to be moved against the pressure within the despatch tube to release the cover latch; but this was not effective in all cases, because the plunger was acted upon directly by a blast of air from the air admission connections. When the difference of compression pressure in the despatch tube due to the emergence of the distant carrier is slight, this blast pressure tends to maintain the latch closed. The present invention provides an unlatching device responsive to compression pressure in

the tube, as distinguished from the blast pressure due to a current of air blown against the pressure-sensitive element.

In the preferred form shown an improved latch mechanism includes a latch 30 made as a bell crank lever pivoted at 31 so as to take over the locking lug O² when moved against the resistance of an adjustable spring 32 held in a bore 33 of the lug 34 forming part of the casing A, by internal pressure in the bore 33 acting upwardly against a piston 35, 38, seated in the bore 33. When in locked position, the latch 30 through the connection 0, 18, 23, 22, 20 preferably holds down on the rod E sufficiently to cause leakage from chamber A³ above piston C² by holding valve E' very slightly away from its seat, as may be delicately adjusted by screw-cap G on rod E. Blow holes x provide a free path to atmosphere for this leakage. A countervailing pressure acting to seat valve C except upon rapid reduction in chamber Y' or tight closure of valve E' is thus prevented. Valve C will remain open until latch 30 is released.

Preferably the spring 33 tending to open latch 30 is made adjustable in accordance with the needs of the particular line of despatch tube by varying the distance between the plunger 35 and the latch 30 by means of the nut 36 and the set collar 37 on the threaded stem 38 of the plunger piston 35. In order to prevent sensitiveness of the piston to blast pressures, admission of air pressure to bore 33 is arranged through a regulated and tortuous passage, including a port 39, a longitudinal port 40 in the cylindrical portion 1 of the casing A, and one opening 41 only of a series of relatively small air openings 47 formed in the despatch end of the despatch tube 2.

It will be observed that the passage 40, 39, is indirect, and that the port 40 is set off from communication with the chamber Y' within the casing A by partitions 48, which prevent access to the passage 40, 39, by direct flow from the air admission valve C and chamber Y'.

The relative pressures within the tube 2 are further controlled by arranging an effective adjustment for the openings 47. One preferred arrangement for this is a sleeve 43 between the tube 2 and casing A having a hand-flange 45 and provided with a number of entrance holes 46 adapted to be moved more or less into register with the holes 47 upon turning the adjusting sleeve 43. Preferably the sleeve 43 is arranged simultaneously to adjust the port 41 by movement into and out of register with it of a hole 42 in the sleeve.

Referring particularly to Fig. 2 it will be noticed that an air blast flowing from a space Y' in the casing A into the despatch

tube 2 flows inwardly in the radial direction of the arrows b, and that there is no direct blast from any of these apertures in the direction of the arrow c which could produce a pressure in the port 40 differing from the true compression or barometric pressure, as distinguished from blast pressure, in the despatch end of the tube 2.

The importance of the last-mentioned provisions will be evident from consideration of the operation of the device, as follows:

A carrier is inserted in the tube 2 and the handle 15 is closed upon the tube. When the cover valve O, O⁴ seats upon the seat a⁵ 80 and the handle is further moved, the valve C unseats promptly and a rush of air occurs through the holes 41. Pressure within the tube 2 behind the carrier builds up promptly, and is communicated through the passage 41, 40, 39, to the plunger 35, and the latch 30 is actuated thereby to hold the cover valve O on its seat and retain valve C off its seat. If no carrier is in the tube, the compression pressure is not enough to operate 90 the latch 30, and accidental or mischievous operation of the handle 15 results in a momentary lifting of valve C only.

When the carrier gathers speed the pressure falls to a balance between the supply 95 coming from the supply pipe as admitted by the regulated ports 47 and the rate of flight of the carrier, but when the carrier emerges at the far end of the despatch tube a sudden drop in the true compression or barometric pressure in the despatch end of the despatch tube ensues. If the line is long and the carrier light, this is not a sufficient difference of pressure reliably to be transmitted through ports 47 and chamber Y' 100 in order to seat the valve C by the pressure of the air trapped in the upper part of the cylindrical space A³. An adjustment of the relative areas of piston C² and valve C for every different initial pressure and every 110 different despatch tube 2 would then be required for infallible operation.

In order to insure seating of the valve C under these circumstances, it is preferred to rely upon causing motion of the valve C, 115 first as a consequence of detection of drop in pressure by the latch mechanism, and second, as a consequence of a sharp release of compression pressure in the tube 2, such as will be effected by opening the cover 120 valve O.

The plunger 35, being sensitive to changes in the pressure in the tube 2 and insensitive to the blast from valve C by reason of the arrangement of the passage 40, 39, and the 125 regulated opening 41, is reliable to act upon the sharp but slight drop in pressure which follows emergence of the distant carrier. Its first effect is to release the valve E' through the connection 0, 0', 18, 23, 22, 20, 130

and thereafter to cause the cover O to be opened, and so produces so marked a drop of pressure in the tube 2 and increase in pressure above piston C² as to insure prompt seating of the valve C by the unbalanced pressure upon it, if closure of valve E' has not already effected this.

The ports 47 and 41, can be adjusted for any duty of tube 2 and any initial pressure 10 in supply line B with ease and without skill, since the conditions of the apparatus call for simultaneous increase and decrease in these openings. When the ports 47 are set to admit enough air to move a carrier to 15 the required height or distance, the pressure-sensitive latch is then in adjustment to open the tube and cut off the air supply upon the exit of the carrier at its distant station.

I claim:—

20 1. Pneumatic despatch tube apparatus having therein a despatch tube, a cover for the terminal of the tube, means to hold the cover closed, a valve for admitting air to the tube to propel a carrier, means for opening the valve active upon closure of the cover, and pneumatic means operating as a consequence of releasing the cover for closing the valve.

25 2. Pneumatic despatch tube apparatus having therein a despatch tube, a cover for the terminal of the tube, means to hold the cover closed, a valve for admitting air to the tube to propel a carrier, a mounting for the cover and means acted on by the mounting 30 for opening the valve upon closure of the cover, operating by release of pneumatic pressure tending to seat the valve, and pneumatic means operating as a consequence of releasing the cover for closing the valve by 35 restoring the seating pressure.

3. Pneumatic despatch tube apparatus having therein a despatch tube, a cover for the terminal of the tube, means to hold the cover closed, a pneumatically operated 45 valve for admitting air to the tube to propel a carrier, means for opening the valve active upon closure of the cover and means operating as a consequence of releasing the cover for closing the valve comprising a mounting 50 for said cover and a valve for controlling pneumatic means for seating said air admission valve.

4. Pneumatic despatch tube apparatus having therein a despatch tube, a main 55 valve for admitting air to the tube to propel a carrier, a piston having a port, a connection between said piston and said main valve, and means comprising a push rod carrying an auxiliary valve, said auxiliary 60 valve opening to the atmosphere a port of greater area than said piston port, for releasing the air pressure on one side of said piston to enable the compressed air on the other side thereof to operate said piston and 65 thereby unseat said main valve.

5. Pneumatic despatch tube apparatus having therein a despatch tube, a main valve for admitting air to the tube to propel a carrier, a piston having a port, a hollow stem connecting said piston and said main 70 valve, and means comprising a push rod operating in said hollow stem and carrying an auxiliary valve, said auxiliary valve opening to the atmosphere a port of greater area than said piston port, for releasing the 75 air pressure on one side of said piston to enable the compressed air on the other side thereof to operate said piston and thereby unseat said main valve.

6. Pneumatic despatch tube apparatus 80 having therein a despatch tube, a cover for the terminal of the tube, a pneumatically operated latch for retaining the cover in closed position, and means for adjusting the transmission of the pneumatic pressure 85 from the despatch tube to the latch operating device.

7. Pneumatic despatch tube apparatus having therein a despatch tube, a cover for the terminal of the tube, a pneumatically 90 operated latch for retaining the cover in closed position, and means for adjusting the transmission of the air under pressure from the despatch tube to the latch operating device, said means comprising a sleeve 95 movable upon the despatch tube to vary the area available for the passage of air from the despatch tube to the pneumatically operated latch.

8. Pneumatic despatch tube apparatus 100 having therein a despatch tube, a cover for the terminal of said tube, a latch for retaining the cover in closed position, pneumatically operated control means for said latch, said control means being operated by 105 pneumatic pressure transmitted from said despatch tube through an orifice therein, and means adapted to vary the effective size of said orifice, said means comprising a collar having an opening therein and movable 110 upon the despatch tube to vary the registration between the orifice in the despatch tube and the opening in the collar.

9. Pneumatic despatch tube apparatus having therein a despatch tube, ports in 115 said tube for supplying compressed air thereto, a cover for the terminal of the tube, a latch for retaining the cover in closed position, pneumatically operated control means for said latch, a passage between the despatch tube and the latch control means, and means for simultaneously adjusting the ports for supply of compressed air to the despatch tube and the passage for transmitting the pneumatic pressure from 120 the despatch tube to the latch operating device.

10. Pneumatic despatch tube apparatus having therein a despatch tube, a cover for the terminal of said despatch tube, a pneu- 130

matically controlled latch for said cover, a plurality of orifices around the circumference of the despatch tube, certain of said orifices being afforded communication between the despatch tube and a source of supply of compressed air, other of said orifices affording communication between the despatch tube and the pneumatic control of the cover latch, and means for simultaneously varying the size of all of said orifices, said means comprising a sleeve rotatable about the despatch tube, and openings in the sleeve brought into varying registration with the orifices in the despatch tube by the rotation of the sleeve.

11. A terminal for pneumatic despatch tube apparatus having therein a despatch tube, a valve controlling a source of pressure fluid for propelling a carrier in said tube, a cover for closing the terminal of the tube, means for controlling the flow of pressure fluid into the tube when the cover is closed, pressure sensitive means for opening the cover adapted to be actuated by pressure in the tube and means for protecting the said pressure sensitive means from the pressure of blast currents in the tube. 20 25

Signed by me at Boston, Massachusetts, this 30th day of October, 1919.

ALEXANDER WATSON.
